United States Patent Office

Des. 229,823
Patented Jan. 8, 1974

229,823

CONTAINER FOR BAKERY PRODUCTS

William Henry Day, Brantford, Ontario, Canada, assignor to W. R. Grace & Co., Duncan, S.C.

Filed Feb. 8, 1972, Ser. No. 224,649

Term of patent 14 years

Int. Cl. D9—03

U.S. Cl. D9—183

FIG. 1

FIG. 2

FIG. 3

FIG. 4

FIG. 5

FIG. 6

FIG. 1 is a perspective view of a container for bakery products showing my new design;

FIG. 2 is a front elevation view thereof;

FIG. 3 is a side elevation view thereof;

FIG. 4 is a top plan view thereof;

FIG. 5 is a bottom plan view thereof; and

FIG. 6 is a top plan view in open position.

I claim:

The ornamental design for a container for bakery products, as shown.
